UNITED STATES PATENT OFFICE.

FRANK J. SHEEHAN, OF CRETE, ILLINOIS.

RAILROAD-SWITCH.

1,302,475.

Specification of Letters Patent. Patented Apr. 29, 1919.

Application filed January 5, 1917. Serial No. 140,792.

To all whom it may concern:

Be it known that I, FRANK J. SHEEHAN, a citizen of the United States, residing at Crete, in the county of Will and State of Illinois, have invented certain new and useful Improvements in Railroad-Switches; and I do hereby declare the following to be a full, clear, and exact description of the invention, such as will enable others skilled 10 in the art to which it appertains to make and use the same.

The invention relates to improvements in railroad switches.

The object of the present invention is 15 to improve the construction of railroad switches and to provide a simple, practical and efficient railroad switch of inexpensive, strong and durable construction adapted to be readily applied to various railroads and 20 capable of enabling the switch to be readily operated by foot pressure.

With these and other objects in view, the invention consists in the construction and 25 novel combination of parts hereinafter fully described, illustrated in the accompanying drawing, and pointed out in the claims hereto appended; it being understood that 30 various changes in the form, proportion, size and minor details of construction, within the scope of the claims, may be resorted to without departing from the spirit or sacrificing any of the advantages of the invention.

In the drawings—

35 Figure 1 is a plan view of a switch constructed in accordance with this invention,

Fig. 2 is a vertical sectional view taken longitudinally of the switch operating mechanism,

40 Fig. 3 is an enlarged longitudinal sectional view of a portion of the same, illustrating the construction of one of the operating devices,

Fig. 4 is a transverse sectional view on 45 the line 4—4 of Fig. 3,

Fig. 5 is a similar view on the line 5—5 of Fig. 3,

Fig. 6 is a detail horizontal sectional view 50 illustrating the arrangement of the side rack bar,

Fig. 7 is a detail sectional view on the line 7—7 of Fig. 2 illustrating the arrangement of the foot plate.

Fig. 8 is an enlarged detail sectional view illustrating the construction for locking the 55 foot plates or pedals.

Like numerals of reference designate corresponding parts in the several figures of the drawings.

In the accompanying drawings in which 60 is illustrated the preferred embodiment of the invention 1—1 designates the main rail of a track and 2 the movable switch rails which are secured by suitable chairs 3 to a connecting bar 4 extending across the 65 track and projecting beyond one side thereof and composed of inner and outer sections 5 and 6. The sections 5 and 6 are connected between the switch rails by a joint 7 consisting of overlapped reduced portions piv- 70 otally connected and adapted to permit independent vertical play of the switch rails to avoid undue strain on the switch operating mechanism. The inner section 5 of the slidable connecting bar extends beneath 75 a platform 8 and is provided with a bottom rack 9 meshing with a gear 10 consisting of a spur pinion mounted on a crank 11 having keyed or otherwise secured to it crank disks or elements 12 and 13 provided with crank 80 pins 14 and 15 located at spaced points at opposite sides of the vertical plane of the crank shaft so that when the crank shaft is rotated one of the crank or wrist pins will be moved downwardly and the other 85 will be carried upwardly. The crank or wrist pin 14 is connected by a link 16 with the inner arm of the lever 17 pivoted intermediate of its ends at 18 to a bracket 19 or other suitable support and connected at 90 its outer arm by a pivot 20 to an operating device 21 carrying a pedal or foot plate 22. The other crank or wrist pin 15 is connected by a link 23 with the inner arm of a lever 24 pivoted at an intermediate point at 25 95 to a bracket 26 and connected at its outer end by a pivot 27 to an operating device 28 carrying the foot pedal or plate 29. Each of the operating devices is substantially L-shaped and has an approximately horizontal 100 arm 30, to which the foot pedal is connected as illustrated at 31.

One of the treadles or foot plates is adapted to be depressed by the foot to move the rack bar longitudinally and carry the movable switch rails in one direction and the 105

- other plate or treadle is adapted to be depressed to move the rack bar and the switch rails in the opposite direction. Any suitable means may be employed for locking the rack 5 bar against accidental movement and the said rack bar is provided with a side rack 32 preferably formed in one wall of the longitudinal slot 33 and meshing with a pinion 34 arranged horizontally and mounted on 10 a vertical shaft 35 extending through the platform and carrying a signal 36 in the form of a lantern. The platform is provided with guide openings 37 for the operating devices of the levers and the rack bar 15 is equipped at the bottom of the longitudinal slot 33 with a guide plate 38 having a relatively narrow longitudinal slot 39 through which extends the lower end of the vertical shaft 35.
- 20 The bottom and side rack bars may, however, be mounted in any other desired manner as will be readily understood.
- The pedals which are movable in opposite directions are locked in their lower or depressed position by means of a pair of oppositely movable catches 40 of approximately L-shape pivoted intermediate of the ends of their long arms at 41 on upwardly projecting keeper portions 42 of a stand 43 designed to 25 be mounted upon and suitably secured to the platform 8. The keeper portions 42, which project upwardly, are provided in their top portions with vertical bifurcations or recesses 44 to receive the pedals 22 and when 30 one of the pedals 22 is in one of the recesses of the keepers 42 of the stand the other pedal is elevated as clearly illustrated in Fig. 8 of the drawings. The catches are provided at their outer ends with short downwardly extending arms which are pivoted at 45 to upwardly extending arms or portions 46 of a 35 slideable operating bar 47. The keepers 42 are provided at the outer sides of their recesses 44 with slots 48 to receive the long 40 arms of the catches and they have horizontally aligned openings 49 located below the recesses and forming guides for the operating rod or bar 47. The slideable operating rod or bar 47 is provided in its upturned terminal portions or arms 46 with slots 50 for the reception of the pivots 45 of the short arms of the catches. The arms 46 are also provided with outwardly extending handles or operating portions 51 which may be moved 45 by the hand or kicked by the foot to effect a sliding of the operating bar or rod. A movement of the operating rod or bar in one direction will raise one of the catches and lower the other and a movement in the opposite 50 direction will produce a reverse movement of the catches. To release either of the foot 55 pedals from a locked position, the bar 47 is moved in one direction to open the keeper 44 having the pedal therein and the other pedal 60 is then pressed downwardly a short distance 65

to elevate the first named pedal from the keeper thus positioning both of the pedals out of their respective keepers. The bar 47 is then moved in a reverse direction opening the other keeper so that on further downward movement of the second named pedal it moves into its respective keeper, and the bar 47 is again moved to close the last named keeper, locking said second named pedal against movement. By means of the catches 70 75 the pedals will be prevented from accidentally moving and the switch rails will be retained in either of their positions.

What is claimed is:—

1. The combination with switch rails, of a 80 connecting bar secured to the switch rails and extending beyond the same and provided with a rack having the teeth arranged horizontally, a crank shaft having a pinion meshing with the said teeth and provided with 85 crank elements having crank portions arranged at spaced points at opposite sides of the vertical plane of the crank shaft and oppositely movable operating devices connected with the crank portions of the crank element 90 and provided with pedals or foot plates.

2. The combination with switch rails, of a connecting bar secured to the switch rails and extending beyond the same and provided with a rack having the teeth arranged horizontally, 95 a crank shaft having a pinion meshing with the said teeth and provided with crank elements having crank portions arranged at spaced points at opposite sides of the vertical plane of the crank shaft, 100 levers fulcrumed intermediate of their ends and extending longitudinally of the rack bar, links connecting one arm of the levers with the crank portions of the crank elements and 105 depressible operating devices connected with the other arms of the said levers and having foot plates or pedals.

3. The combination with switch rails, of a connecting bar secured to the switch rails and extending beyond the same and provided 110 with a rack having the teeth arranged horizontally, a crank shaft having a pinion meshing with the said teeth and provided with crank elements having crank portions arranged at spaced points at opposite sides of the vertical plane of the crank shaft, levers 115 fulcrumed intermediate of their ends and extending longitudinally of the rack bar, links connecting one arm of the levers with the crank portions of the crank elements and depressible operating devices connected with the other arms of the said levers and having 120 foot plates or pedals, said operating devices being provided with horizontal arms adjustable longitudinally to vary the throw of the 125 operating devices.

4. The combination with switch rails, of a connecting bar extending beyond the switch rails and secured to the same, said connecting bar being provided with rack teeth, a 130

crank shaft provided with a pinion meshing with the teeth of the rack bar, levers fulcrumed intermediate of their ends and connected at one end with the crank shaft and 5 depressible operating devices connected with the other ends of the levers and movable in opposite directions.

In testimony whereof I affix my signature in presence of two witnesses.

FRANK J. SHEEHAN.
